UNITED STATES PATENT OFFICE.

ARTHUR C. KLECKNER, OF RACINE, WISCONSIN, ASSIGNOR TO WEBSTER ELECTRIC COMPANY, OF RACINE, WISCONSIN, A CORPORATION OF WISCONSIN.

MAGNETO.

1,417,746.

Specification of Letters Patent. Patented May 30, 1922.

Application filed January 3, 1921. Serial No. 434,559.

To all whom it may concern:

Be it known that I, ARTHUR C. KLECKNER, a citizen of the United States, residing at Racine, in the county of Racine and State of 5 Wisconsin, have invented certain new and useful Improvements in Magnetos, of which the following is a full, clear, concise, and exact description, reference being had to the accompanying drawings, forming a part of 10 this specification.

My invention relates to magnetos, and more particularly to ignition magnetos of the inductor type. Among its objects my invention contemplates the provision of a 15 magneto that is sturdy in its construction, that comprises a minimum number of parts, that is capable of being cheaply manufactured and that is very efficient, both magnetically and electrically. Other objects of 20 the invention will hereinafter appear.

In attaining the objects of my invention, I provide a novel arrangement and combination of parts, which co-operate to carry into effect what I regard as a new 25 theory or principle of magneto operation, which will be most clearly understood from a detailed description read in connection with the accompanying drawings, in which

Figure 1 is a front elevational view of a 30 magneto embodying the improvements of my present invention;

Figure 2 is a horizontal sectional view taken on line 2—2 of Figure 1;

Figure 3 is a vertical sectional view illustrating the rotor element in its "cocked" 35 position;

Figure 4 is a vertical sectional view taken on the line 4—4 of Figure 3;

Figure 5 is a horizontal sectional view 40 taken on line 5—5 of Figure 4;

Figure 6 is an isolated elevational view of a unit which comprises the three legs of the trifurcated core structure of the magneto;

Figure 7 is a top plan view of the unit shown in Figure 6; and

Figure 8 is a fragmentary vertical sectional view similar to Figure 3, but illustrating the rotor at the position occupied 50 thereby when it reaches the end of its "recoil" movement.

Similar characters of reference refer to similar parts throughout the several views.

The particular embodiment of my inven-

tion herein shown and described comprises 55 a permanent horseshoe magnet 7, the north and south poles of which are seated respectively upon the pole pieces 8 and 9. Each of the pole pieces is conveniently formed of soft iron laminæ which are secured together 60 by a plurality of rivets 10—10 and are clamped in position between the non-magnetic side plates 11 and 12. The lower portions of plates 11 and 12 are drawn toward each other and are held tightly in engagement with the pole pieces by screws 65 13—13, which extend through registering apertures in the side plates and pole piece laminæ. Each of the pole pieces 8 and 9 is provided with an arcuate polar face which 70 is concentric with the axis of the rotor structure presently to be described. Side plates 11 and 12 are conveniently provided with bosses 14—14 carrying studs 14^a—14^a, which constitute means for attaching the 75 magneto to a bracket or other support in a well-known manner.

Each of the side plates 11 and 12 is conformed to provide a vertically elongated recess 15 in its inner face, and is likewise provided with an inwardly projecting bearing 16. Bearings 16—16 are disposed with their axes aligned and at right angles to a straight line between the poles of magnet 7.

The trifurcated core structure comprises 85 three principal parts; namely, legs A, B, and C, and the crossbar D, which when the several parts are assembled in operative position lies against, and is held firmly in magnetic contact with, the upper ends of 90 legs A, B, and C. The lower extremities of legs A, B and C are provided with arcuate faces concentric with the faces of pole pieces 8 and 9.

Each of the core structure legs A, B and 95 C consists of a plurality of soft iron laminæ which are secured to, and carried as a unit with, nonmagnetic plates 17—17 by means of rivets 18—18. The unit comprising plates 17—17 and core legs A, B and C is 100 held in position by screws 19—19, which pass through side plates 11 and 12 and have threaded engagement with apertures 20—20 in the said nonmagnetic plates 17—17. The only wound leg of the core structure is the 105 middle leg B, which is provided with a coil or winding 21, one end of which is grounded to the core structure in a wellknown manner

(not shown), and its other end is provided with the insulated conductor terminal 22. The coil is held against downward displacement by non-magnetic plates 17-17 5 and against upward displacement by the core structure crossbar D. Crossbar D comprises a plurality of soft iron laminæ secured together by rivets 23-23. It is embraced and held against lateral and longitudinal 10 displacement by a rectangular flange 24 which is carried on the under face of the top plate 25. Screws 26-26, carried by top plate 25, press against crossbar D and hold the same tightly in magnetic contact with the upper ends of the core structure legs A, B and C. Top plate 25 is in turn secured to the side plates 11 and 12 by a plurality of screws 27-27.

The rotor structure comprises a nonmagnetic block 28, into which trunnions 29 and 30 are threaded and pinned as is most clearly illustrated in Figure 4. Nonmagnetic block 28 is provided with angularly related grooves, which are arranged to receive the inductor elements E and F, each of which consists of a plurality of soft iron laminæ held in proper relation to each other and to block 28 by rivets 31-31. Each of the inductor elements is provided with convex 30 faces at its extremities arranged to co-operate with the concave faces of the pole pieces and core structure legs as is clearly illustrated in Figures 3 and 8.

The magneto shown being of the oscillating type, the trunnion 29 is provided with the yoke 32, which is held rigidly on the trunnion by a key and nut, as shown. The yoke is provided with oppositely disposed arms carrying the usual rollers, which co-operate with the inner ends of the operating springs 33-33. The outer ends of the operating springs co-operate with rolls carried by roller posts 34-34, which are formed integral with, and project laterally from, 45 extensions 35-35 of side plate 11. Rotor trunnion 30 is provided with a push finger 36, which is held rigidly thereon by a pin and nut, as is clearly shown in Figure 4. Push finger 36 is, of course, arranged and 50 adapted to be engaged, moved against the tension of operating springs 33-33, and released, by a push rod or other engine driven actuator (not shown) in a manner well-known to persons familiar with the construction and operation of oscillating ignition magnetos.

Figure 3 illustrates the rotor in the position which it occupies after it has been "cocked" against the tension of operating 60 springs 33-33, and is about to be released by the engine driven actuator which co-operates with push finger 36. In this position the magnetic circuit is traced from pole piece 8 through inductor element E to the lower extremity of core structure leg B,

thence through leg B and across bar D to leg A, thence through leg A to inductor element F, through inductor element F to pole piece 9, and thence around the magnet to pole piece 8. When the rotor is released 70 by the engine driven actuator, and is snapped to the position shown in Figure 8, the direction of the flux traversing the coil carried by leg B is reversed, the magnetic circuit now being traced from pole piece 8 75 to inductor element E, thence up through core structure leg C, thence across bar D to coil carrying leg B, thence downwardly through leg B, thence through inductor element F to pole piece 9, and thence around 80 the magnet to polepiece 8. It will be seen that the flux is traversing the coil carrying leg B in an upward direction when the rotor is "cocked" and in a downward direction when the rotor is at the end of its "recoil" 85 movement. The peak of the wave of current created in coil 21, due to the reversal of flux through core leg B, is attained when inductor element E is just leaving leg B, and inductor element F is just approaching 90 leg B. At this instant the rate of flux change through leg B is at its maximum.

It will be noted that the construction and arrangement of parts hereinbefore described 95 enables me by a comparatively slight angular movement of the rotor, to secure a complete reversal of flux through the coil carrying portion of the core structure, which is of course of great advantage, in that it makes it possible to secure a large output 10 of electrical energy from a magneto embodying a minimum of magnet steel in its construction. The machine shown comprises a single coil which is placed in a very accessible position and is removable for inspection, repair or replacement. Other advantages of the structure illustrated will suggest themselves to persons familiar with the art to which my invention relates.

While for the purpose of illustration I 110 have chosen to illustrate my invention as it may be incorporated in a low tension magneto of the oscillating type, it is to be understood that the novel features of the device of my invention are just as applicable 115 to high tension magnetos as they are to those of the low tension type. Furthermore, some at least of the salient features of the machine shown will be found to be of decided advantage when incorporated in 120 either high or low tension magnetos of the rotary inductor type.

Having thus described my invention, what I claim is new and desire to secure by Letters Patent of the United States is:

1. In a magneto, a substantially E-shaped core structure, a winding on the middle leg of the core structure, a magnet, and inductor means adapted when in one position to establish a low reluctance path for flux 130

- between one of the magnet poles and the wound core leg, and between the other magnet pole and a first one of the unwound core legs, said inductor means adapted when in 5 another position to establish low reluctance paths for flux between the first-mentioned magnet pole, and the second unwound core leg, and between the other magnet pole and the wound core leg.
- 10 2. In a magneto, a substantially E-shaped core structure, a winding on the middle leg of the core structure, a magnet, and a rotor element comprising a pair of inductor elements, each inductor element adapted when 15 in one position to establish a low reluctance path for flux between one pole of the magnet and the middle leg of the core structure, and when in another position to establish a low reluctance path for flux between the 20 same pole and an unwound core leg, said inductor elements being so related to each other and to the magnet and core structure that when either of said inductor elements co-operates with the middle leg of the core 25 structure and one pole of the magnet, the other inductor co-operates with the other magnet pole and an unwound leg of the core structure.
3. In a magneto, a magnet provided with 30 pole pieces, a substantially E-shaped core structure, a generating winding on the middle leg of said core structure, and a rotor comprising inductors which, when the rotor is in one position, establish a flux path 35 through the wound leg of said core and one of the unwound legs, and which, when the rotor is in another position, establish a flux path through the wound core leg and the other unwound core leg, the direction of 40 flux flow through the wound core leg being in different directions under the two conditions stated.
4. In a magneto, a magnet, a substantially E-shaped core structure, a winding on the 45 middle leg of the core structure, and a rotor provided with a pair of inductor elements, a first one of the inductor elements adapted, when the rotor is in one position, to establish a low reluctance path for flux between the 50 north pole of the magnet and the middle leg of the core structure while the other inductor element is establishing a similar path for flux between the south pole of the magnet and a first one of the outside legs of 55 the core structure, said first inductor element also adapted, when the rotor is in another position, to establish a low reluctance path for flux between the north pole of the magnet, and the second outside leg of the 60 core structure, at which time the second inductor element is establishing a similar path for flux between the south pole of the magnet and the middle leg of the core structure.
- 65 5. In a device of the class described, an E-shaped core structure of magnetic mate-
- rial, a generating winding on the middle leg thereof, a magnet, and means when operated adapted first to establish a path between the magnet poles which includes the wound core leg and one of the unwound core legs, 70 and which subsequently establishes a path between the magnet poles which includes the wound core leg and the other unwound core leg, the direction of flux flow through the wound core leg being different under the two 75 conditions stated.
6. A magneto comprising a magnet, a trifurcated core structure, a winding on the middle leg of the core structure, and a rotor comprising a pair of inductor elements, one 80 of said inductor elements adapted, when the rotor is operated, alternately to connect the middle core leg and one of the outside core legs with one pole of the magnet, the other inductor element operating in synchronism 85 with the first, alternately to connect the other outside core leg and the middle core leg with the other magnet pole.
7. In a magneto, a magnet, a generating 90 winding, a trifurcated core structure upon the middle leg of which the generating winding is carried, and a pair of inductor elements arranged when operated to reverse the direction of flux through the winding by first connecting one magnet pole with the extremity of the middle leg of the core structure, and simultaneously connecting one of the outer legs of the core structure with the opposite magnet pole, and then connecting the last-mentioned magnet pole with the extremity of the middle leg of the core structure, and simultaneously connecting the first-mentioned magnet pole with the other outside leg of the core structure.
8. In a magneto of the oscillating type, a 95 magnet provided with pole pieces, a trifurcated core structure, a generating winding on the middle leg of the core structure, and a rotor provided with a pair of inductor elements, each of which co-operates with one of 100 the pole pieces during both the cocking and recoil movements of the rotor, one inductor adapted to co-operate with the middle leg of the core structure when the rotor is cocked, and on the recoil of the rotor to co-operate 110 with a first one of the outside legs of the core structure, the other inductor element arranged to co-operate with the second outside leg of the core structure when the rotor is cocked and on the recoil to co-operate with 115 the middle leg of the core structure.
9. In a magneto of the oscillating type, the combination with a permanent magnet, a trifurcated core structure, a winding on the middle leg of the trifurcated core structure, 120 and a rotor provided with a pair of inductor elements, one of said inductor elements adapted, when the rotor is cocked, to establish a low reluctance path for flux between a first pole of the magnet and the middle leg 125
- 130

of the core structure, and on the recoil to establish a similar path for flux between the same magnet pole and a first one of the outside core structure legs, the other inductor element adapted, when the rotor is cocked, to establish a low reluctance path for flux between the other outer leg of the core structure and the second pole of the magnet, and on the recoil of the rotor to establish a similar path for flux between the same magnet pole and the middle leg of the core structure.

10. A magneto of the oscillating type comprising a horseshoe magnet provided with oppositely disposed pole pieces, a rotor 15 operating between the pole pieces, said rotor provided with a pair of inductor elements each of which is adapted to co-operate with the same pole piece during the cocking and recoil movements of the rotor, a trifurcated 20 core structure disposed between the magnet poles and above the rotor, a winding on said core structure, one inductor element co-operating with the middle leg of the core structure when the rotor is cocked, and the 25 other co-operating with a first one of the outside legs when the rotor is cocked, the first inductor element being carried into co-operating relation with the other outside leg of the core structure, and the second inductor element being carried into co-operating relation with the middle leg of the core structure, when the rotor is recoiled.

11. A magneto comprising a magnet, pole pieces for the magnet provided with concave 35 polar faces, a trifurcated core structure, the legs of which are provided with concave extremities concentric with the concave faces of the pole pieces, and a rotor, comprising a pair of inductor elements having extremities 40 adapted to co-operate with the concave faces of the pole pieces and core structure legs.

12. A magneto comprising a permanent horseshoe magnet, pole pieces for the magnet provided with concave polar faces, side 45 plates disposed on opposite sides of the magnet, a rotor journaled in said side plates, operating between the pole pieces and disposed with its axis at right angles to a straight line between the magnet poles, and 50 a trifurcated core structure located above the rotor, and disposed in the space bounded by the side plates and magnet legs, the legs of said core structure comprising concave extremities concentric with the faces of the 55 pole pieces, said rotor comprising a pair of inductor elements provided with convex extremities adapted to co-operate with the concave faces of the pole pieces and core struc-

ture legs to vary the magnetic flux through the winding carried by the core structure.

13. A magneto comprising in combination with a permanent magnet, pole pieces therefor, a rotor operating between the pole pieces and a winding-carrying trifurcated core disposed above the rotor, said rotor provided with inductor elements adapted to co-operate with the pole pieces, and with the extremities of the trifurcated core structure legs to vary the magnetic flux through the winding carried by the core structure.

14. A magneto comprising in combination with a permanent magnet, pole pieces therefor, a trifurcated core structure carried in the space between the magnet legs and above said pole pieces with the legs of said core structure extending downwardly, and a rotor operating between said pole pieces and provided with inductor elements adapted to co-operate with said pole pieces, and the trifurcated core leg extremities, to vary the magnetic flux through the winding carried by said core structure.

15. A magneto comprising a housing, oppositely disposed pole pieces in said housing, a magnet having its poles in contact with 85 said pole pieces, a core structure which comprises three substantially vertical legs, and a cross bar which normally contacts with the upper extremities of said legs, core structure side plates to which said legs are 90 secured, a generating winding upon the middle core leg, means for removably securing said core structure side pieces to said housing, and means for clamping the cross bar 95 against the upper extremities of said core structure legs.

16. A magneto comprising a housing, oppositely disposed pole pieces in said housing, a magnet having its poles in contact with said pole pieces, a core structure comprising 100 a plurality of substantially vertical legs, a cross bar which normally contacts with the upper extremities of said legs, a generating winding inductively related to one of said core structure legs, core structure side 105 plates to which said legs are secured, means for removably securing said core structure side pieces in said housing, and means for clamping the cross bar against the upper ends of said legs.

In witness whereof, I hereunto subscribe my name this 27th day of December, 1920.

ARTHUR C. KLECKNER.
